UNITED STATES PATENT OFFICE.

WILLIAM J. LANG, OF BALTIMORE, MARYLAND.

GAME.

No. 826,339.

Specification of Letters Patent.

Patented July 17, 1906.

Application filed September 9, 1905. Serial No. 277,880.

To all whom it may concern:

Be it known that I, WILLIAM J. LANG, a citizen of the United States of America, residing at Baltimore, in the State of Maryland, 5 have invented new and useful Improvements in Games, of which the following is a specification.

This invention relates to game-boards of the surface-projectile type, and particularly 10 to that class in which the board is provided with seats for the reception of a projected ball or sphere, said seats being variously arranged to designate different scores, faults, or various points or penalties in the playing 15 of the game when the ball rolls into one or the other of said seats.

The object of the invention is to provide a game-board of this class which is simple of construction, adapted to be inexpensively 20 manufactured, and whereby the playing of the game of base-ball may be simulated.

The preferred embodiment of the invention is illustrated in the accompanying drawings, in which—

25 Figure 1 is a plan view of the game-board, and Fig. 2 is a longitudinal section of the ball-projector.

The numeral 1 in the drawings represents the game-board, the upper face of which constitutes the playing-surface and which is provided with a surrounding upwardly-projecting vertical rim 3, forming a marginal boundary wall inclosing the playing-space. The board may be of any preferred outline 35 form, but is preferably made rectangular, as shown in the present instance, and provided at the far end of a playing-surface with a strip 4, arranged upon the inner side of the adjacent portion of the guard-wall 3 and having curved terminals 5, forming deflectors, at the adjacent corners to cause the ball or projectile to rebound or to be guided toward the center of the playing-surface.

The forward portion of the playing-surface 45 has printed or otherwise formed thereon a diamond 6, representing the corresponding portion of a base-ball field, the bases at the corners of the diamond being indicated by square spaces suitably marked or designated 50 in any other desired manner. The space inclosed by the diamond, representing the so-called "infield," is provided at the center with a space marked P, indicating the pitcher's position, and at various points in 55 said space or infield are pockets or seats 7, formed by circular openings or indentations

in the board and variously marked "Out," "Sacrifice," and "Double play," denoting various points made or played in the game when the ball is batted by the batter to such 60 position.

The rear portion of the playing-surface, or that portion beyond the diamond, represents the "outfield" and has spaces marked, respectively, "L. F.," "C. F.," and "R. F.," 65 designatory of the usual positions of the left, center, and right fielders. The outfield may also be provided with a space marked "S. S.," indicating the deep-playing position of the short stop, and other spaces denoting playing 70 positions of the other infielders. The outfield is provided with a plurality of variously-arranged seats 8, similar to the seats 7, and suitably designated to indicate one, two, and three base-hits, home runs, and outs, and also 75 double plays, if desired, indicating points to which the ball when batted may be driven for safe hits or probable outs. In the playing 80 of the game the ball employed is propelled from a position adjacent to the home base alternately by the players or in such order as may be determined by any desired rule. In the event that one player represents a side or base-ball team it will of course 85 be understood that he will continue to play until his side is put out in an obvious manner, according to the conventional rules of the game, after which the other player will play in turn, and the two alternate in playing until a full game of nine or any desired number 90 of innings is played.

The ball 9 is adapted to be batted or propelled by a projector comprising a casing 10 of oblong rectangular form, occupying a groove or recess 11 in the front portion of the flange 3 and resting upon the surface of the board and suitably fastened in position. The outer end of this casing is closed, while the inner end thereof is open for the insertion 95 of the ball. The upper wall 12 of the casing 100 has a depressed or inwardly-deflected portion 13, forming a shoulder 14 to limit the inward movement of the ball and properly contract the casing for the reception of a knocker-block or follower 15, adapted to be forced forward by an impelling-spring 16, disposed between the same and the outer end wall of the casing to project the ball across the playing-surface. To the block is attached a stem or shank 17, which is slidable in the slot 18 in the depressed portion 13 and provided with 105 an exposed finger-piece 20, whereby the 110

block may be retracted to compress the spring and release the block to allow the spring to project the block to discharge the ball.

5 It will be readily understood that when the ball is propelled across the playing-surface it will be finally arrested by and will occupy one of the seats 7 or 8, which according to its designating character will indicate an out, a hit, or other possible play in the game. Runs or scores are counted when a player succeeds in making the required hit or hits or other plays sufficient to advance a man around the diamond. Positions on the bases may be 15 determined by using suitable colored pieces of material or dummy figures, as will be readily understood.

Considerable skill may be acquired in projecting the ball with greater or less force to 20 make a contemplated play, and the device

will also afford considerable interest, amusement, and instruction in the playing of the national game.

Having thus described the invention, what I claim is—

25 A game-board having a playing-surface provided with a rectangular boundary wall, a diamond and an outfield, the spaces forming the diamond having variously-arranged projectile-detainers properly designated to indicate plays in the game of base-ball, a projectile-propelling device arranged at the front of the playing-surface, and curved deflectors at the corners of the outfield.

30 In testimony whereof I affix my signature in presence of two witnesses.

35 WILLIAM J. LANG.
